SYSTEM OF CONTROL.

1,327,795.

Specification of Letters Patent. Patented Jan. 13, 1920.

Application filed June 19, 1917. Serial No. 175,594.

To all whom it may concern:

Be it known that I, CHARLES C. WHITTAKER, a citizen of the United States, and a resident of Wilkinsburg, in the county of Allegheny and State of Pennsylvania, have invented a new and useful Improvement in Systems of Control, of which the following is a specification.

My invention relates to systems of control and especially to the automatic regulation thereof under conditions of slipping or skidding of the associated vehicle wheels in regenerative control systems for locomotives and the like.

In the prior art, various schemes have been proposed to eliminate slipping or skidding of dynamo-electric machines during periods of vehicle propulsion or retardation, such action, in general, being dependent upon the difference in voltage of the armatures of a normally operating and a slipping or skidding machine. However, so far as I am aware, no system has been devised for absolutely preventing an immediate recurrence of such abnormal conditions after they have once been remedied, and, consequently, it has been possible in such prior art systems for successive "slipping" and "rail-gripping" to occur until such time as the vehicle speed has become materially reduced.

It is the object of my present invention to provide a relatively simple and effective means for precluding the possibility of an immediate recurrence of slipping or skidding conditions in the dynamo-electric machines of a locomotive or the like, whereby such abnormal conditions are remedied immediately upon their recurrence, and certain machine conditions are so changed that immediate recurrence of slipping or skidding is obviated.

My invention is illustrated in the accompanying drawings, wherein Figure 1 is a diagrammatic view of the main circuits of a control system embodying my present invention; Fig. 2 is a diagrammatic view of certain auxiliary circuits for governing the operation of the main machines that are shown in Fig. 1; and Fig. 3 is a diagrammatic view of an electric locomotive unit embodying a plurality of dynamo-electric machines to which my invention may be applied.

Referring first to Fig. 3 of the drawings,

the structure shown comprises a locomotive cab 1 which is suitably supported upon a plurality of articulated trucks 2 and 3 of suitable design and which respectively embody a plurality of sets of driving wheels 4 and 5 that are adapted to run upon track rails 6, in accordance with the usual practice. A plurality of dynamo-electric machines M1 and M2 are provided and may be associated with the wheels of the various trucks in any suitable manner, as by driving mechanisms 7 and 8 of a familiar type.

Referring now to Fig. 1, the system shown comprises supply-circuit conductors Trolley and Ground; the dynamo-electric machines M1 and M2, which are respectively provided with commutator-type armatures A1 and A2 and field windings F1 and F2 of the series type; a plurality of balancing resistors R1 and R2 that are associated with the respective machine windings in a manner to be set forth; an auxiliary exciting source for the main field windings, preferably comprising a motor-generator set 10; a variable resistor 11 that is connected in the main-field-winding circuits and is adapted to be regulated by a controller 12 having an automatic actuating mechanism 13; a limit switch 14 for governing the operation of the mechanism 13, in accordance with circuit conditions; and a plurality of voltage-relay devices 15 and 16 that are connected across the respective main armatures A1 and A2 for an automatic governing purpose to be described.

The motor-generator set 10 is shown as comprising a driving or motor armature 20 that is mechanically associated, in any suitable manner, as by a shaft 21, with a generator or exciting armature 22. A main or exciting field winding 23 and a compensating field winding 24 are provided for the driving armature 20, and similar field windings 25 and 26 are associated with the generating armature 22.

The controller 12 comprises a movable contact segment 29 that is preferably mounted upon a drum 30 and is of suitable configuration for successively engaging a plurality of stationary control fingers 31 that are connected to various points of the field-winding-circuit resistor 11, whereby the active circuit value thereof may be varied.

The actuating mechanism 13 is of a familiar electrically-controlled, pneumatically

operated type and comprises a pinion 32 which is rigidly secured to the operating shaft 33 of the controller 12 and is adapted to mesh with a horizontally-movable rack member 34, the opposite ends of which constitute pistons 35 and 36 that travel within suitable operating cylinders 37 and 38, respectively. A normally closed valve 39, having an actuating coil "On", is associated with the outer end of the cylinder 37, while a normally open valve 40, having an actuating coil "Off", normally effects communication between an inlet pipe or passage 41 and the outer end of the cylinder 38. The normally closed valve 39 is likewise provided with an inlet pipe or passage 42, and any suitable source of fluid pressure (not shown) may be connected to the pipes 41 and 42.

20 The operation of the electrically-governed apparatus 13, without regard to the circuit connections effected thereby, may be set forth as follows: Upon concurrent energization of the actuating coils "On" and "Off", the initial unbalanced fluid-pressure conditions, whereby the mechanism is biased to the illustrated position, are reversed, that is, fluid pressure is admitted to the cylinder 37 and is released from the other cylinder 38 to effect a movement of the pistons 35 and 36 toward the right. To arrest such movement, at any time, it is merely necessary to de-energize the "Off" coil, whereupon balanced high-pressure-fluid conditions immediately obtain in the apparatus, and a positive and reliable stoppage thereof is secured.

25 To produce a return movement of the controller, the actuating coils "On" and "Off" are concurrently de-energized, whereby fluid-pressure conditions in the apparatus revert to the original unbalanced state, and the desired backward movement is effected.

30 Inasmuch as the particular circuit arrangements for inaugurating accelerating or regenerative operation of the illustrated system are immaterial to my present invention, which is capable of a wide variety of applications, I have not deemed it necessary to illustrate or describe such arrangements but have eliminated, in so far as possible, main-circuit switches and the like which, it is understood, will be normally employed during the operation of the system.

35 Assuming, therefore, that the system is operating under regenerative conditions, for example, the main circuits are established from the trolley through conductor 50 to junction-point 51, where the circuit divides, one branch including conductor 52, main armature A1, conductor 53 and balancing resistor R1 to a second junction-point 55, and the other branch traversing conductor 56, main armature A2, conductor 57 and the balancing resistor R2 to the junction-point 55, whence a common circuit is completed

through conductor 58, the actuating coil for the limit switch 14 and conductor 59 to the negative supply-circuit conductor Ground.

40 The exciting circuit for the main field windings is established from the positive terminal of the auxiliary generating armature 22 through conductors 61, 62 and 58 to the junction-point 55, where the circuit divides, one branch traversing the balancing resistor R1, main field winding F1 and conductor 63 to a junction-point 64, and the other branch including the balancing resistor R2 and main field winding F2 to the junction-point 64, whence a common circuit is continued through the variable auxiliary 45 resistor 11, conductor 66 and compensating field winding 26 to the negative terminal of the generating armature 22.

45 The further circuit is established from the trolley, through conductor 67, compensating field winding 24, armature 20 and exciting field winding 23 for the auxiliary driving motor, conductor 68, exciting field winding 25 for the auxiliary generating armature 22 and thence through conductor 62 to ground.

50 The illustrated main-circuit connections are not of my present invention, but are fully set forth and claimed in a co-pending application of Rudolf E. Hellmund, Serial No. 44,443, filed August 9, 1915, and assigned to the Westinghouse Electric & Manufacturing Company. Consequently, only a brief description of the operation thereof will be necessary to afford a thorough comprehension of the present invention.

55 As indicated by the solid arrows, representing main armature or regenerated current, and the dotted arrows, denoting exciting or main-field-winding current, both of these currents traverse either one of the balancing resistors R1 and R2 in the same direction. Hence, upon an incipient increase of regenerated current in the main armature A1, for example, the corresponding voltage drop across the resistor R1 immediately and inherently reduces the portion of the auxiliary generating-armature voltage that is available for delivery to the main field winding F1, or, in other words, the excitation is varied oppositely to the regenerated current traversing the main armature A1. The converse action occurs whenever an incipient decrease of current obtains in the main armature. In this way, a substantially constant regenerated current is maintained in the main armature, irrespective of supply-circuit-voltage fluctuations and the like.

60 To compensate for the gradual decrease of vehicle speed during the retardation period, the excitation of the main field windings may be increased by gradually short-circuiting the variable resistor 11, and this result is accomplished automatically by the auxiliary system that is shown in Fig. 2,

comprising the actuating coils "On" and "Off" for the controller-regulating mechanism 13, the auxiliary contact members of the relay devices 14, 15 and 16, an auxiliary 5 switching device 45 for short-circuiting the contact members of the voltage relays 15 and 16 under predetermined conditions, a master controller MC having a plurality of operative positions *a* and *b* for primarily governing the system operation and an auxiliary 10 source of energy, such as a battery B.

Upon actuation of the master controller to its initial operative position *a*, a circuit is established from the positive terminal of 15 the battery B through conductor 69, control fingers 70 and 71, which are bridged by contact segment 72 of the master controller, conductor 73, coöperating stationary and movable contact members 74 and 75 of the 20 voltage relays 15 and 16, respectively, in their upper or high-voltage positions, conductors 76 and 77, the actuating coil "On" and conductor 79 to the negative terminal of the battery B.

25 If the master controller is moved to its position *b*, a further circuit is completed from the contact segment 72 through control finger 80, conductor 81, coöperating stationary and movable contact members 82 of the 30 limit switch 14, in its low-current position, and the actuating coil "Off" to the junction-point 78 and the negative conductor 79.

The forward actuation of the controller 12 to gradually short-circuit the resistor 11 35 is automatically governed, in accordance with regenerated current conditions, by the limit switch 14, in conformity to a familiar practice, under normal operating conditions.

The lifting of the limit switch interrupts 40 the circuit of the "off" coil and thus arrests the movement of the controller 12, as previously explained.

However, in case either of the main armatures A1 and A2 and the sets of vehicle 45 wheels 4 and 5 that are respectively associated therewith should slip or skid, the voltage of that armature is materially reduced, as is well understood, whereby the corresponding voltage relay 15 or 16 will 50 drop to its open-circuit position to deenergize the "on" actuating coil. At the same time, the regenerated current will be sufficiently high to lift the limit switch 14 to 55 interrupt the energizing circuit for the actuating coil "Off." Consequently, since both actuating coils for the mechanism 13 are concurrently deenergized, a backward movement of the controller 12, to reinsert a greater amount of the variable resistor 11 in 60 the main-field-winding circuit and thereby weaken the main-machine excitation, takes place until voltage and speed conditions of the two main armatures are again equalized, whereupon normal operation of the system, 65 as previously described, will be resumed and,

furthermore, no immediate recurrence of such slipping or skidding conditions will obtain, by reason of the weakened main-field-winding excitation. In this way, I provide a control system, wherein slipping or 70 skidding conditions of a dynamo-electric machine are immediately remedied, and no further alternate "slipping" and "rail-gripping" can possibly obtain until a considerable time interval has elapsed and speed conditions of the vehicle have materially decreased. 75

In lieu of varying the resistor 11 to compensate for the gradual decrease of vehicle speed, other well-known methods, such as 80 changing the active circuit value of the resistors R1 and R2, or of resistors that are connected in shunt to the exciting field winding 23, may be utilized.

If it is desired to exclude the voltage relays 15 and 16 from active circuit regulation during the accelerating period, this result may be accomplished by closing the switching device 45 (Fig. 2), whereby a circuit is completed from the conductor 73 85 through conductor 83, switching device 45 and conductor 84 to the conductor 77, or, in other words, the coöperating contact members 74 and 75 of the voltage relay devices 16 and 15, respectively, are short-circuited 90 and rendered ineffective.

I do not wish to be restricted to the specific circuit connections or arrangement of parts herein set forth, as various modifications thereof may be effected without departing from the spirit and scope of my invention. I desire, therefore, that only such limitations shall be imposed as are indicated in the appended claims.

I claim as my invention: 105

1. In a system of control, the combination with a plurality of dynamo-electric machines associated with a common load, of single means for simultaneously regulating the operation thereof, means dependent upon a material departure in the speed of either machine from normal for actuating said single regulating means to weaken the machine excitation, whereby further speed departures under the existing operating conditions 110 are prevented.

2. In a system of control, the combination with a plurality of dynamo-electric machines associated with a common load, of single means for simultaneously regulating the operation thereof, and means dependent upon the "slipping" of any machine for actuating said single regulating means to modify the machine excitation, whereby said "slipping" is remedied and further "slipping" under the existing general machine conditions is obviated. 120

3. In a system of vehicle control, the combination with a plurality of dynamo-electric machines for operating the vehicle along 130

- track rails, of single means for simultaneously regulating the operation of said machines, and means dependent upon the "slipping" of any machine for actuating said single regulating means to weaken the machine excitation, whereby said "slipping" is remedied by causing the corresponding machine to "grip" the rails and successive "slipping" and "rail-gripping" is obviated.
10. 4. In a system of regenerative vehicle control, the combination with a plurality of momentum-driven dynamo-electric machines for operating the vehicle along track rails, of means for separately exciting said machines, means for regulating such excitation, and means dependent upon the "slipping" of any machine for actuating said regulating means to modify the machine excitation, whereby said "slipping" is remedied by causing the corresponding machine to "grip" the rails and successive "slipping" and "rail-gripping" is obviated.
15. 5. In a system of control, the combination with a plurality of dynamo-electric machines severally having armatures and field windings, of single means for simultaneously varying the excitation of said field windings, and means dependent upon a material departure in the speed of either machine from normal for actuating said single varying means to weaken the field excitation, whereby the machine speeds are equalized and immediate recurrence of said speed departure is prevented.
20. 6. In a system of control, the combination with a plurality of dynamo-electric machines severally having armatures and field windings, of single means for simultaneously varying the excitation of said field windings, and means dependent upon the "slipping" of any machine for actuating said single varying means to modify the field excitation, whereby said "slipping" is remedied and immediate recurrence thereof is obviated.
25. 7. In a system of control, the combination with a plurality of dynamo-electric machines severally having armatures and field windings, of means for separately exciting said field windings, a controller for regulating such excitation, means for operating said controller in either direction, and means dependent upon a material voltage difference of either machine from normal for actuating said operating means to weaken the field excitation, whereby said voltage difference is eliminated and immediate recurrence thereof is prevented.
30. 8. In a system of control, the combination with a plurality of dynamo-electric ma-

chines severally having armatures and field windings, of means for separately exciting said field windings, a controller for regulating such excitation, an electrically-governed apparatus for operating said controller in either direction, and means dependent upon the "slipping" of any machine for energizing said electrically-governed apparatus to modify the field excitation, whereby said "slipping" is remedied and immediate recurrence thereof is prevented.

9. In a system of control, the combination with a plurality of dynamo-electric machines severally having armatures and field windings, of means for separately exciting said field windings, a controller for regulating such excitation, an apparatus having a plurality of actuating coils for operating said controller in either direction, and a plurality of relay devices energized from the respective armatures and severally provided with contact members that are connected in circuit with one of said coils under predetermined conditions.

10. In a system of control, the combination with a plurality of dynamo-electric machines severally having armatures and field windings, of means for separately exciting said field windings, a controller for regulating such excitation, an apparatus having a plurality of actuating coils for operating said controller in either direction, and a plurality of relay devices connected across the respective armatures and severally provided with contact members that are connected in series-circuit relation with one of said coils only when the voltage difference of each machine from normal is less than a predetermined value.

11. In a system of control, the combination with a plurality of dynamo-electric machines severally having armatures and field windings, of means for separately exciting said field windings, a controller for regulating such excitation, an apparatus having a plurality of actuating coils for operating said controller in either direction, and a plurality of relay devices connected across the respective armatures and severally provided with contact members that are connected in series-circuit relation with one of said coils only when the voltage difference of each machine from normal is less than a predetermined value, and another relay device governed by the main-machine current for opening and closing the circuit of the other coil.

In testimony whereof I have hereunto subscribed my name this 31st day of May, 1917.

CHARLES C. WHITTAKER.
